UNITED STATES PATENT OFFICE.

AUGUSTE CHANARD, OF PARIS, FRANCE.

RECEPTACLE FOR INCENDIARY AERIAL BOMBS.

1,313,068.

Specification of Letters Patent. Patented Aug. 12, 1919.

Application filed April 5, 1919. Serial No. 287,881.

To all whom it may concern:

Be it known that I, AUGUSTE CHANARD, of 5 Rue de Bruxelles, Paris, France, have invented Receptacles for Incendiary Aerial Bombs, of which the following is a full, 5 clear, and exact description.

In my patent application Ser. No. 247,298 filed July 29th 1918, there is described and shown a receptacle for aerial incendiary 10 bombs, in which the body of the receptacle is constituted by two rigid shells which affect, when they are connected together, the form of a solid of revolution and the longitudinal edges of which, placed at a certain 15 interval from each other, are connected by a band or surface of easily fusible or combustible material.

It results from this constructive arrangement that the direct or indirect ignition of 20 the incendiary material contained in the receptacle brings about the combustion and the disappearance of the material connecting the shells, and, consequently, the separation of these latter and the deposit of the 25 incendiary material upon the target struck by the bomb.

The present addition has for its object a new method of constructing the receptacle for aerial incendiary bombs forming the 30 subject matter of the patent application Ser. No. 247,298 filed July 29th, 1918.

It comprises, broadly, two semi-cylindrical shells soldered on to the short sides of a receptacle of rectangular section, so as to provide 35 a certain space between their vertical edges and to form two distinct compartments: one, a central one, formed by the receptacle of rectangular section and containing a suitable thermite or highly inflammable mixture, and the other bounded by the two shells, surrounding the first one and containing an incendiary composition such as that set forth in my co-pending application Ser. No. 245,003, filed July 15, 1918, which 40 comprises a substance, such as pitch, tar or resin, which is not readily inflammable under normal conditions, a solvent therefor, and a substance capable of supporting the combustion thereof.

50 This constructive arrangement of the receptacle permits a projectile to be obtained which affects the form of a solid of revolution, symmetrical on its transverse axis, and receiving the fuse at one of its ends and the tail at the other end.

The central receptacle contains the auto-

thermic mixture and is constructed of an easily fusible material and is provided on its exposed faces, with vent holes closed by fusible plates. Into these vent holes open 60 the relay fire communicating orifices the tubes of which containing the quick match wicks open on the other hand, into the chamber of the breech plug.

When the fuse acts, the fire is transmitted 65 through the medium of the quick match wicks, to the thermite and, at the same time, the fusible plates closing the vent holes are melted. The result is that the auto-thermic mixture burns in an open vessel, bringing 70 about the disappearance of the receptacle which contains it and ignites the incendiary composition which will be entirely deposited on arriving at the target, owing to the opening of the two shells insulated from each 75 other by the fusion of the central receptacle.

The accompanying drawing shows, by way of example, the new method of obtaining the receptacle for incendiary bombs, arranged according to the principle above described.

Figure 1 is an external view in perspective.

Fig. 2 is a vertical section on the line A—A 85 of Fig. 3.

Figs. 3 and 4 are horizontal sections on the lines B—B and C—C respectively of Fig. 2.

Fig. 5 is a vertical section on the line D—D of Fig. 2. 90

As will be seen in the drawing, the present receptacle for incendiary bombs has a receptacle *a*, of parallelepiped form, on to the external faces of which are soldered the semi-cylindrical shells *b* which are fixed so as to leave a small interval *c* between their longitudinal edges and to form, as has been stated above, a solid of revolution symmetrical on its transverse axis.

This constructive arrangement forms thus 100 two compartments: the central one *a*, of fusible or combustible material and containing the auto-thermic mixture, the other *d* surrounding the central compartment and containing an incendiary composition, such 105 for example as that which forms the subject matter of the patent application Ser. No. 245,003 filed July 15th, 1918.

The central compartment *a* has, at its upper part, a filling opening *a'* closed by a 110 plug *a''*. The outer compartment *d* has also an upper opening for filling *d'* closed by a

plug d^2 screwed into a ring e soldered onto the upper part of the shells b .

The lower part of these shells is likewise connected by a ring f into which is soldered 5 a cover g closing in the base of the receptacle d .

The front ring f of the projectile thus constructed, receives, on the other hand, by screwing, the breech plug h which carries 10 a fuse of any suitable type.

Two relay fire tubes i are arranged in the central compartment a and are filled with quick match wicks. Their lower ends open into the chamber h' of the nose plug h by 15 passing through the cover g soldered onto the ring f .

The fire communicating openings i' of these tubes i open at the level of vent holes in the central compartment a .

20 These vent holes are formed by small screw threaded cylinders j fixed on the body of the bomb and opening freely into the receptacle a . They receive threaded rings k which are provided on their inner faces, 25 with fusible washers k' of tin for example.

Finally, the receptacle is completed by tongues or masks l intended to close up the spaces left by the assemblage of the shells b and of the central receptacle a .

30 The compartment d being filled with a suitable incendiary composition, such, for example, as that described in patent application Ser. No. 245,003 filed July 15th, 1918, and the central compartment a being likewise 35 filled with a suitable thermite, the ignition of this thermite is obtained in the following manner:

The bomb having been dropped from an aeroplane or a dirigible balloon, for example, and the fuse having acted, the quick match wicks contained in the relay fire tubes i instantaneously ignite and melt the fusible washers k' closing the vent holes k .

40 The disappearance of these washers has 45 as a result to permit the special thermite contained in the compartment a to burn in an open vessel. The combustion of this auto-thermic mixture, which takes place very rapidly, determines the fusion or the combustion of the said compartment a , so that the shells b become separated, and the projectile is split longitudinally while the incendiary composition contained in the receptacle d is brought to a high temperature 50 and ignited on the very target which it has struck.

The method of construction above de-

scribed, it must be quite understood, is only given by way of example, and although it appears to offer the most practical advantages, as much by reason of the facility of stamping out as by the simplicity of manufacture, it is obvious that its form and its dimensions may vary, without thereby altering the invention. 60

65 I claim:

1. The receptacle formed by two semi-cylindrical shells, soldered by their longitudinal edges to the short sides of a receptacle of rectangular section, so as to form a certain 70 interval between these longitudinal edges and to form a projectile affecting the form of a solid of revolution, symmetrical on its transverse axis and divided into distinct compartments: a central one, formed by the 75 receptacle of rectangular section and intended to contain a suitable thermite, and the other, bounded by the two shells surrounding the first one and intended to contain an incendiary composition; the central compartment, constructed of material incapable of resisting the action of heat, being provided with vent holes which are formed by fusible washers and into which open the relay fire openings, the tubes of which, 80 provided with quick match wicks, open on the other hand into a chamber formed in the nose plug carrying the fuse, for the purpose of determining, by the action of the fuse, the instantaneous destruction of the fusible 85 washers closing the vent holes and the ignition of the auto-thermic mixture which burns in an open vessel, brings about the disappearance of the receptacle which contains it and ignites the incendiary composition 90 which is poured out upon the target struck in consequence of the opening of the two shells insulated from each other by the fusion of the central compartment. 95

2. Receptacle for incendiary bombs comprising an elongated compartment having end and side walls adapted to be destroyed by the action of heat, a substantially hemi-cylindrical compartment adjoining said elongated compartment on each side thereof, 100 a fuse carrying plug, a fusible closure inserted in a hole in one of the end walls of said elongated compartment, and a tube extending from said plug to said fusible closure. 105

110 The foregoing specification of my receptacle for incendiary aerial bombs, signed by me this 14th day of March 1919.

AUGUSTE CHANARD.
